PAPER MARKING APPARATUS

Arthur M. Wickwire, Jr., Mountain Lakes, N. J.,
 assignor to Chambon Corporation, Garfield,
 N. J., a corporation of New York

Application April 5, 1938, Serial No. 200,143

9 Claims. (Cl. 101—153)

This invention relates to the art of coating and marking paper where the paper is fed in webs between a marking and an impression cylinder; and it is particularly directed to an improved press arrangement for preventing offset or backstain on the unmarked side of the web.

In the coating and marking of certain paper, such as carton stock or stock of medium weight which is to be used subsequently in making corrugated board, it is customary to coat or mark one side of the paper only by passing a web between an intaglio marking cylinder and a resilient impression cylinder. A doctor blade may or may not be used in conjunction with the marking cylinder, depending on the coloring or marking effect desired. The presses used in marking this type of paper usually employ extremely long cylinders to accommodate the wide stock being colored. It is desirable to use an impression cylinder of small diameter, since the pressure required for the proper transfer of ink to the paper is more readily obtained by a cylinder of small diameter than by one of large diameter. However, the smaller the diameter of the impression cylinder is, the weaker it will be, so that when the pressure required for satisfactory transfer of ink is applied at the ends of the cylinder, it may result in an undesirable longitudinal bending of said cylinder. Hence, it is customary and necessary to apply the required pressure to the resilient impression cylinder by means of a back-up or pressure cylinder which is adapted to distribute the pressure throughout the length of the impression cylinder. Effective threading of the web, which aids in preventing warping and rippling, is then provided by feeding the web around the surface of both the back-up and impression cylinders.

Such presses are used at present and function satisfactorily when the web width is the same as the impression cylinder used. However, it is not always possible or convenient to provide a different press or impression cylinder for each size of stock, and it often becomes necessary to run webs of a desired width through a press having rollers considerably wider than the web. When this is done, it has been found that an undesirable offset or backstain occurs on the uncolored side of the web causing a definite waste of both paper and ink at the edge portions. It was heretofore thought that this offset or backstain was caused by the mere presence of ink on the portions of the impression cylinder extending beyond the edges of the web and contacting the ink bearing marking cylinder. Hence, all suggestions for

eliminating this difficulty have involved the provision of supplementary means either for preventing the transfer of ink from the marking cylinder to the impression cylinder or for removing the ink from said exposed portions of the impression cylinder, or combinations of both of these means. While such systems have been successful to a certain degree in eliminating the difficulty, they have not functioned efficiently under all conditions of operation. Furthermore, such supplementary devices constitute an additional source of adjustment and trouble in the operation of the press.

I have discovered that it is possible to mark webs of different widths using a single press having cylinders of maximum width without the above mentioned supplementary devices and in such a manner that there will be no undesirable offset or backstain on the uncolored side of the web.

In accordance with my invention, this result may be accomplished by providing an improved press of the usual three roller type in which the line of contact between the back-up or pressure cylinder and the impression cylinder is interrupted in such a manner that said line of contact never overlaps the edges of the web. To do this, I have provided a pressure cylinder having a central web contacting portion slightly shorter than the web of minimum width, end contact portions positioned to contact the impression cylinder at points beyond the maximum width of web, and portions of reduced cross sectional area between said contacting portions. I may provide a plurality of slideable rings or collars on said reduced portions so that the extent of the contact portions may be increased and changed to accommodate webs of different widths and still be such that the line of contact between the pressure cylinder and the impression cylinder does not overlap the edges of the web.

Specific embodiments of apparatus for carrying out my invention are illustrated in the accompanying drawing in which:

Figs. 1 and 2 are, respectively, front and side elevations, partly in section, of an intaglio marking press provided with my improved offset preventing pressure cylinder;

Fig. 3 is an enlarged detail view of a pressure cylinder having movable collars or rings on the reduced portions thereof; and

Fig. 4 is a vertical sectional view taken substantially along the line 4—4 of Fig. 3.

As shown in the drawing, a web 10, of paper or carton stock which is to be coated, is fed from a

55

suitable and conveniently located source of supply to an intaglio printing press 12. This press, which may be of any suitable construction, comprises base members 14 and side frames or stands 16 in which is journalled an engraved or knurled marking cylinder 18. The marking cylinder 18 may be driven at the desired speed by a motor 20 and rotates in a bath of marking material 22 contained in a fountain housing 24 which is secured by means of brackets 26 to the side frames 16. I have not shown a doctor blade or other wiping means cooperating with the marking cylinder 18, but it is to be understood that one may be used, if desired.

15 Mounted above the marking cylinder and driven thereby are a resilient impression cylinder 28 and a pressure or back-up cylinder 30. The pressure cylinder has each end of its shaft journalled in a slideable housing member 32, while each end of the impression cylinder shaft is rotatably mounted in a bearing block 34 which is adapted to slide up and down in a slot 36 provided in the associated housing member 32. Suitable rails or guideways 38 are provided on the side frames 16 for slidably receiving the housing members 32 which may be moved toward and away from the marking cylinder 18 by means of suitable threaded shafts 40 cooperating with internally threaded hubs 42 provided on the side frames 16. By turning a hand wheel 44 provided on the upper end of each threaded shaft 40, the slideable housing may be moved downward or upward so as to regulate the pressure on the cylinders.

35 Web 10 is fed in at the top of the unit over the pressure cylinder 30, then around the impression cylinder 28 to the printing or marking line. Due to the rotation of the marking cylinder in the bath 22, a quantity of the marking medium collects in the bite between the marking and impression cylinders where it is transferred to the web 10 in the desired quantities as determined by the pressure employed, the depth of the intaglio markings and the presence or absence of a doctor.

40 As thus far described, the press construction is conventional and because of the resiliency of the impression cylinder, the portions thereof which extend beyond the edges of the web 10 will contact the marking cylinder and ink will be transferred to such portions of the surface of the impression cylinder. Unless special provision is made, this ink will be transferred to the edge portions of the back of the web and cause an undesirable backstain or offset. In order to prevent this and still transmit sufficient pressure to the impression cylinder to maintain an effective transfer of ink, I have modified the construction of the usual uniformly cylindrical pressure or

55 back-up cylinder.

60 As shown, the pressure cylinder 30 is not of uniform cross sectional area throughout its length but is provided with a central web contacting section or portion 46 and end contact portions 48. The central portion 46 is shown as slightly shorter than the width of the web 10 which is the smallest size stock that is ever marked in the press 12. The end contact portions 48 are located so that they will not contact any portion of the widest web run through the press. Thus, there are intermediate portions 50 of the cylinder, between the central portion 46 and the end contact portions 48, which are of reduced cross sectional area and greater in length

75 than one half the difference between the widest

and narrowest webs used on the press. In this manner, the line of contact between the pressure cylinder and the impression cylinder is interrupted and will never overlap the edges of the web. I have found that this construction transmits the required pressure to the impression cylinder and effectively prevents offset or backstain upon the encolored side of the web.

5 In Figs. 3 and 4, there is shown another form of improved pressure cylinder 52, which similarly to the cylinder 28, has a central web contacting portion 54, end contacting portions 56, and intermediate portions 58 of reduced cross sectional area. Preferably, however, the end contacting portions 56 are removable and the reduced sections 58 provided with guide bars or keys 60 for the reception of a plurality of rings or collars 62 which may be set in any adjusted position by means of set screws 64. These collars may be used to increase the width of the central web 20 contacting portion 54 and the end contact portions 56 when a web 66, of greater width than the web 10, is to be colored or marked. By providing a series of collars 62 of uniform width with a space 68, greater than the width of any one 25 collar, between them, the bearing surface may be maintained at a maximum and adjusted to accommodate webs of any standard widths without permitting the line of contact between the pressure cylinder and the impression cylinder 20 ever to overlap the edges of the web.

Usually the pressure or back-up cylinder is provided with an outside metal surface. However, in order to prevent scorching of the resilient impression cylinder at the points where the line of contact is interrupted, the bearing or contact surfaces of my improved pressure cylinder and the collars 62 may be provided with sheaths 70 of rubber or other suitable resilient material.

40 Although there are advantages in using the 40 collars 62 on my improved pressure cylinder, it is to be understood that the first described construction shown in Fig. 1 will function efficiently with webs considerably wider than the central web contacting portion 46. Moreover, if desired, the pressure cylinder may be constructed without any permanent central web contacting portion and such a contacting portion could be provided entirely by the slideable rings or collars. Various other changes may be made in the construction and certain features may be employed without others, without departing from my invention or sacrificing any of its advantages.

45 What I claim is:

1. In a machine for marking webs of different 55 widths, a marking cylinder wider than the web being marked; an impression cylinder wider than said web; and a pressure cylinder, substantially as wide as the impression cylinder, having a central web contacting portion which is no wider 60 than the web.

2. In a machine for marking webs of different widths, the combination of a marking cylinder; an impression cylinder; and a back-up cylinder 65 substantially as wide as the impression cylinder and having a web contacting portion, the construction and arrangement of the parts being such that the line of contact between the back-up cylinder and the impression cylinder is interrupted adjacent the web contacting portion 70 so as not to overlap the edges of the web.

3. In a machine for marking webs of different widths, a marking cylinder wider than the web being marked; an impression cylinder wider than said web; and a pressure cylinder having a cen- 75

tral web contacting portion which is no wider than the web, and end contacting portions spaced from said central contacting portion and the edges of said web.

5. 4. In a machine for marking webs of different widths, the combination with a marking cylinder and an impression cylinder wider than the web being marked, of a pressure cylinder having a central web contacting portion, and means for 10 adjusting said central web contacting portion so that the width thereof will correspond substantially with the width of the web.

5. In a machine for marking webs of different widths, the combination with a marking cylinder 15 and an impression cylinder wider than the web being marked, of a pressure cylinder having a plurality of slidable collars mounted thereon and adapted to be adjusted to provide a central web contacting portion which is narrower than the 20 web.

6. In a machine for marking webs of different widths, the combination with a marking cylinder and an impression cylinder wider than the web being marked, of a pressure cylinder comprising 25 a central web contacting portion, portions of reduced cross sectional area on each side of said central contacting portion, and movable collars mounted on said reduced portions.

7. In a machine for marking webs of different widths, the combination with a marking cylinder and an impression cylinder wider than the web being marked, of a pressure cylinder comprising 5 a central web contacting portion, portions of reduced cross sectional area on each side of said central contacting portion, movable collars mounted on said reduced portions, and means for preventing movement of said movable collars with respect to said reduced portions. 10

8. In a machine for marking webs of different widths, a back-up cylinder having a centrally disposed web contacting portion which is no wider than the web and end contacting portions spaced from said web contacting portion for 15 bearing against an impression cylinder at points beyond the edges of the web.

9. In a machine for marking webs of different widths, a pair of spaced side frames; a marking cylinder wider than the web being marked and 20 journaled in said side frames; an impression cylinder wider than said web and journaled in said side frames; and a pressure cylinder journaled in said side frames and having a central web contacting portion which is no wider than 25 the web.
